(57) **CLAIM**

The ornamental design for a notebook computer housing, as
shown and described.

DESCRIPTION

FIG. 1 is a front perspective view of a notebook computer
housing shown in an open configuration according to a first
embodiment of our design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a detail perspective view of a portion of FIG. 1;

FIG. 9 is a front perspective view of a notebook computer
housing shown in an open configuration according to a second
embodiment of our design;

FIG. 10 is a top view thereof;

FIG. 11 is a detail perspective view of a portion of FIG. 9;

FIG. 12 is a front perspective view of a notebook computer
housing shown in an open configuration according to a third
embodiment of our design;

FIG. 13 is a detail perspective view of a portion of FIG. 12;

FIG. 14 is a front perspective view of a notebook computer
housing shown in an open configuration according to a fourth
embodiment of our design;

FIG. 15 is a detail perspective view of a portion of FIG. 14;

FIG. 16 is a front perspective view of a notebook computer
housing shown in an open configuration according to a fifth
embodiment of our design;

FIG. 17 is a detail perspective view of a portion of FIG. 16;

FIG. 18 is a front perspective view of a notebook computer
housing shown in an open configuration according to a sixth
embodiment of our design;

FIG. 19 is a detail perspective view of a portion of FIG. 18;

FIG. 20 is a front perspective view of a notebook computer
housing shown in an open configuration according to a seventh
embodiment of our design;

FIG. 21 is a front view thereof;

FIG. 22 is a right side view thereof;

FIG. 23 is a left side view thereof;

FIG. 24 is a top view thereof; and,

FIG. 25 is a detail perspective view of a portion of FIG. 24.
Broken lines are environmental only and form no part of the
claimed design. Dash-dot lines represent bounds of associated
portions of the claimed design and form no part of the
claimed design.
